UNITED STATES PATENT OFFICE.

HERMAN B. MEYER, OF CHICAGO, ILLINOIS.

DESIGN FOR A LAMP BASE.

Application filed February 18, 1929. Serial No. 30,118. Term of patent 3½ years.

To all whom it may concern:

Be it known that I, HERMAN B. MEYER, a citizen of the United States, residing at Chicago, in the county of Cook and State of Illinois, have invented a new, original, and ornamental Design for a Lamp Base, of which the following is a specification, reference being had to the accompanying drawings forming a part thereof.

Fig. 1 is a fragmentary top plan view of the base, the balance of the ornamentation within the outline being a repetition of the fragment shown.

Fig. 2 is a fragmentary view in elevation of the base, the balance of the ornamentation within the outline being a repetition of the fragment shown.

I claim:

The ornamental design for a lamp base, substantially as shown.

HERMAN B. MEYER.
